(57) **CLAIM**

The ornamental design for a nozzle for vacuum cleaner, as shown and described.

DESCRIPTION

1. Nozzle for vacuum cleaner

1.1 : Perspective

1.2 : Front

1.3 : Back

1.4 : Left

1.5 : Right

1.6 : Top

1.7 : Bottom

The article has transparent materials. The broken lines shown in Figures 1.3 and 1.7 depict portions of the nozzle for vacuum cleaner that form no part of the claimed design.
